UNITED STATES PATENT OFFICE

2,638,387

GUIDING DEVICE FOR TOOL MACHINES

Jørgen Bech, Lyngby, Denmark

Application July 26, 1947, Serial No. 763,915
In Denmark October 5, 1943Section 1, Public Law 690, August 8, 1946
Patent expires October 5, 1963

3 Claims. (Cl. 308—6)

1

The present invention relates to a guiding device for tool machines that are provided with a guide rod supporting the cutter head of the machine, and a casing encompassing this guide rod, said casing and guide rod being relatively displaceable.

The hitherto known guiding devices of this kind are subjected to the essential drawback that the guide rod contacts the interior wall of the case with its entire surface. To reduce the resulting friction and thus provide increased mobility, comparatively large quantities of a lubricant must be applied to the casing and guiding rod, but notwithstanding this lubrication the mobility acquired will not always be sufficient to meet the demands of finer work, because a small displacement of the one member in relation to the other will take place in jerks, which render impossible the accomplishment of fine work.

The object of the present invention is to provide means for remedying this drawback, thus rendering possible the accomplishment of smooth running of the casing and the guide rod relatively. This is obtained by the introduction between the casing and the guide rod of a number of rollers which in two planes at a right angle to each other are arranged on opposing sides of the guide rod, and of which rollers that or those disposed on the one side of the guide rod is or are adjustable.

By these means the friction between the relatively movable members is reduced to a minimum, and the friction pressure between the rollers and the guide rod may be adjusted to any desired value. The continued lubrication of the relatively movable members is avoided, and owing to the presence of the rollers any mutual displacement of the members may be performed smoothly.

In a preferred manner of construction the casing carries on two adjoining sides a number of rollers, and on each of the opposing sides a radially adjustable roller disposed midways in relation to the former rollers. By means of this construction a comparatively simple manner of regulation of the adjustable roller is obtained.

The invention is furthermore explained in the following description with reference to the accompanying drawing, in which one embodiment of the invention is illustrated.

Fig. 1 is a top elevation of a guiding device according to the invention as applied to a milling machine of which only parts pertinent to the invention are included,

2

Fig. 2 a side elevation of the device shown in Fig. 1.

Fig. 3 a sectional view on line III—III in Fig. 1 on a somewhat increased scale, and

Fig. 4 a sectional view on line IV—IV in Fig. 3.

Referring to the drawing, 1 indicates the guide rod of the milling machine, which guide rod carries the cutter head (not shown), and 2 indicates a casing accommodating the guide rod 1, with which in this casing the guide rod is lengthwise displaceable but not rotatable. The casing is rigidly attached to the machine frame, and the casing and guide rod have square cross section. To each of two adjoining walls of the casing there are applied interspaced casings 3 and 4, and 5 and 6 respectively, each pair of casings carrying a non-adjustable roller 7 and 8 respectively. To each of the walls opposed to the first mentioned walls of the casing midways between the rollers 7 and 8 is attached a single pair of casings, 9 and 10 respectively, each pair carrying a radially adjustable roller, 11 and 12 respectively.

As shown in Figs. 3 and 4, the casing 9 has a shaft 13 extending transversely to the casing 2, and within the casing carries a bushing 14 that is connected to the shaft by means of a U-shaped driver member 15, the base of which engages a longitudinal groove 16 in the shaft 13, whereas the legs of the driver member 15 are inserted in holes 17 in the bushing 14. When the shaft 13 is rotated within the roller 11 the bushing 14 will accompany it in this rotational movement. The groove 16 extends to the ends of the shaft thus allowing the extraction of this shaft from the bushing.

Each end of the bushing 14 is turned down to form uniform eccentric paths 18 for the ball bearings 19 that are provided with an exterior ring 20. When the bushing 14 with its eccentric paths 18 is rotated by means of the shaft 13, the ball bearings and with them the exterior ring 20 will alter their position in relation to the shaft, and upon completion of each adjustment of the exterior ring 20 upon the shaft, the latter is clamped in position by means of a clamping nut 21.

The adjustable roller in the bearing 10 is constructed in a corresponding manner.

It will be understood that the invention described above can equally well be applied to a machine in which the guide rod is rigidly attached to the machine frame, and the casing is movable in relation to the guide rod. Furthermore, more than two non-adjustable rollers may be applied to the two adjoining sides, as likewise

on the opposing sides may be applied adjustable rollers corresponding in number to the intervals between the non-adjustable rollers. The means for adjustment of the rollers may be others than those described and illustrated, as likewise the driver member between the shaft and the bushing may be arranged in any other adequate manner.

The guide rod may furthermore have other cross section than square. It may for instance 10 be triangular or polygonal in cross section. Nor is it necessary to interpose ball bearings between the eccentric paths on the bushing and the cylindrical roller, as these members may contact each other directly. Instead of eccentric bearings at each end of the bushing, this member may be provided with a single, or with several eccentric bearings in any part between its ends.

I claim:

1. A guiding device for tool machines comprising a cutter head guiding rod of angular cross section, and a casing surrounding said rod, said rod and said casing being relatively displaceable longitudinally with respect to each other, two relatively interspaced pairs of rollers mounted on axles rigidly secured in the said casing, one roller of each pair bearing on one side of the said guiding bar, the other roller of each pair bearing on an adjoining side of the guiding bar, another pair of rollers spaced from the aforesaid two pairs of rollers and mounted on axles adjustably secured in said casing, the rollers of the said other pair of rollers each bearing on one of the other two adjoining sides of the said guiding rod.

2. A guiding device for tool machines comprising a cutter head guiding rod of angular cross section, and a casing surrounding said rod, said rod and said casing being relatively displaceable longitudinally with respect to each other, two relatively interspaced pairs of rollers mounted on axles rigidly secured in the said casing, one roller of each pair bearing on one side of the said guid-

ing bar, the other roller of each pair bearing on an adjoining side of the guiding bar, another pair of rollers spaced from the aforesaid two pairs of rollers, each roller bearing upon one of the other two adjoining sides of the said guiding rod, an axle for each roller in the last-mentioned pair of rollers eccentrically mounted in the casing for adjustment of the said rollers in relation to the guiding rod.

3. A guiding device for tool machine comprising a cutter head guiding rod of angular cross section, and a casing surrounding said rod, said rod and said casing being relatively displaceable longitudinally with respect to each other, two relatively interspaced pairs of rollers mounted on axles rigidly secured in the said casing, one roller of each pair bearing on one side of the said guiding bar, the other roller of each pair bearing on an adjoining side of the guiding bar, another pair of rollers spaced from the aforesaid two pairs of rollers, each roller bearing upon one of the other two adjoining sides of the said guiding rod, an axle for each said other rollers having an eccentric bore, a bolt extending longitudinally through said bore for securing said axle in said casing, and means for preventing rotation of said bolt and said axle relative to each other, but permitting longitudinal displacement of said bolt in said bore.

JØRGEN BECH.
